Application June 16, 1937, Serial No. 148,616

26 Claims. (Cl. 172—239)

Our invention relates to electric discharge apparatus and has particular relation to power supply apparatus. A description of our invention, together with experimental data is published beginning on page 1200 of the November 1936, issue of Electrical Engineering.

It is an object of our invention to provide apparatus that shall operate as its own automatic regulator for supplying power from a source of electrical energy to a load.

Another object of our invention is to provide power supply apparatus that shall incorporate a regulator which functions to maintain the potential across the load independent of the potential of the source.

Still another object of our invention is to provide power supply apparatus that shall automatically regulate itself to maintain the load potential constant in spite of variations in the source potential.

A further object of our invention is to provide power supply apparatus that shall automatically regulate itself to maintain the load potential constant regardless of variations in the load current.

A still further object of our invention is to provide power supply apparatus by the operation of which it shall be possible to adjust the compounding to any desired condition.

An additional object of our invention is to provide power supply apparatus that shall automatically regulate itself to maintain the load current constant in spite of variations in the source potential.

A further additional object of our invention is to provide power supply apparatus that shall automatically regulate itself to maintain the load potential substantially constant in spite of variations in the load current.

Another additional object of our invention is to provide a power supply apparatus incorporating grid controlled electric discharge paths wherein the discharge paths shall function to provide automatic regulation.

A more specific object of our invention is to provide a power rectifier that shall operate as its own automatic regulator.

An additional specific object of our invention is to provide apparatus of the type that shall operate as its own automatic regulator for rectifying the power supplied by a polyphase source to a direct current load.

Another specific object of our invention is to provide a power supply system in which regulation shall be attained without the use of movable contacts.

An ancillary object of our invention is to provide a highly tractable system for supplying power to an electro-dynamic machine.

Another ancillary object of our invention is to provide for an electric motor a power supply sys-

tem of such character that the operation of the electric motor shall be adjustable with facility.

A further ancillary object of our invention is to provide for an electric motor a power supply system of such character that the speed of the motor shall be controlled by controlling a current of small magnitude.

A still further ancillary object of our invention is to provide a highly tractable power supply system for a direct current motor.

More generally stated, it is an object of our invention to provide a power supply system that shall be automatically regulable and adjustable, so that its operation may be made to conform to a wide variety of desired conditions.

According to our invention, we interpose one or more discharge devices or discharge paths, each of which has a control electrode and a plurality of principal electrodes and a gaseous medium, between the source and the load. A constant potential of polarity such as to energize the discharge device is impressed between the control electrode and one of the principal electrodes. The magnitude of this potential is selected so large, compared to the critical control potential of the discharge device, that random variations which may arise in the magnitude of the critical control potential of any one discharge device or between the critical control potentials of the different discharge devices are substantially masked. The critical control potential is defined as the potential between the control electrode and a principal electrode of a discharge device at which the discharge device passes from a deenergized to an energized condition for a given potential between the principal electrodes. For control potentials more negative than the critical control potential, the discharge device if initially deenergized remains deenergized, for more positive control potentials it is energized.

On the constant potential another potential dependent upon and, in specific cases, proportional to the load potential is superimposed. The latter potential is of polarity opposite to the former potential and of such magnitude that the critical control potential is only at times exceeded.

Specifically when the source of electrical energy whereby the load is to be supplied is of the polyphase type, a discharge device is inserted between each phase and the load and the aforementioned potentials are impressed between the control electrode and a principal electrode of each of the discharge devices. In this case the total control potential comprising the sum of the two potentials mentioned above rises above the critical control potential periodically. We have found that when properly adjusted, a system of this type operates to maintain the load potential

constant in spite of variations in the source potential.

Under certain conditions, it is desirable that the load potential should be maintained constant independently of variations in the load current. At times the more general problem of compounding is involved. These problems may be solved at the same time by superimposing on the two potentials above mentioned a potential proportional to the load current. This potential may be derived by inserting current transformers in the source and applying the rectified output of these transformers to the control circuits of the discharge devices.

The foregoing procedure may be designated as current compounding. We have also found that potential compounding may be of considerable utility in maintaining the load current or load potential or both constant independently of variations in source potential and the load potential constant independently of variations in load current. Potential compounding is attained by adding a potential, derived from the source and rectified, to the constant potential and the potential dependent on the load potential in the control circuits of the discharge device. By adjusting the magnitude of the rectified potential derived either from the current flow from the source or from the potential of the source, the compounding may be adjusted to any desired condition.

As an outgrowth of our development in automatic regulation, we have discovered a system for controlling an electro-dynamic machine in a comparatively simple and inexpensive manner. The electro-dynamic machine is supplied from a source through discharge devices of the gaseous type. In the control circuits of the discharge devices, a constant potential of magnitude large compared to the critical control potential and of a polarity such as to energize the discharge devices is impressed. On this potential another potential derived from current transformers in the power source and essentially proportional to the current through the machine is superimposed. The latter potential is of opposite polarity to the former potential. We have found that a machine supplied in this manner operates at a substantially constant current independently of variations in potential as long as the potential of the source is sufficient to supply the potential of the machine, and at a substantially constant potential independently of the variations in current when the potential of the source is insufficient to supply the potential of the machine. During starting, therefore, an electro-dynamic machine supplied in this manner operates in the first region mentioned above, while during its normal functioning it operates in the other region mentioned above. The system discussed above may be applied with particular advantage where a direct-current motor having independent excitation is supplied from a polyphase alternating source. Such a motor may be controlled by controlling its excitation and this object may be accomplished by varying the small current delivered by a photo-electric cell.

The novel features that we consider characteristic of our invention are set forth with particularity in the appended claims. The invention itself, however, both as to its organization and its method of operation, together with additional objects and advantages thereof, will best be understood from the following description of

specific embodiments when read in connection with the accompanying drawings, in which:

Figure 1 is a diagrammatic view showing an embodiment of our invention;

Fig. 2 is a graph illustrating the operation of Fig. 1;

Fig. 3 is a diagrammatic view showing a modification of our invention that incorporates current compounding;

Fig. 4 is a graph showing the functioning of a system such as is disclosed in Fig. 3 under certain circumstances;

Fig. 5 is a diagrammatic view of a modification of our invention involving the application of the principles illustrated in Fig. 4 to an electro-dynamic machine;

Fig. 6 is a diagrammatic view showing a modification of our invention as disclosed in Fig. 5;

Fig. 7 is a graph showing further features of the modification shown in Fig. 3;

Fig. 8 is a diagrammatic view of a modification of our invention involving both current and potential compounding, and;

Fig. 9 is a diagrammatic view of a modification of our invention as it is applied to a double three-phase rectifier system.

The apparatus shown in Fig. 1 comprises a polyphase source 11, the output of which is connected to a suitable supply transformer 13. The secondary 15 of the transformer 13 is connected in star and supplies a load 17 through a plurality of discharge devices 19, 21 and 23, a discharge device being interposed between each of the windings 25, 27 and 29 of the secondary and one terminal of the load. The other terminal of the load 17 is connected to the neutral point 29 of the secondary 15 through a reactor 30. Each of the discharge devices 19, 21 and 23 comprises an anode 31, a hot cathode 33, a control electrode 35 and a suitable ionizing medium. The ionizing medium may be provided by an inert gas such as argon or neon at a pressure of 2 or 3 millimeters of mercury or it may be the vapor of a mercury globule located within the container of the discharge device.

Each of the discharge devices 19, 21 and 23 has a so-called arc-like characteristic. One aspect of such a characteristic is abruptness of response. For a given anode-cathode potential, the device is substantially nonconductive as long as the control-electrode-cathode potential is more negative than a potential which we have above designated as the critical control potential. When the control-electrode-cathode potential becomes more positive than the critical control potential, the discharge device becomes conductive and passes current, the magnitude of which is independent of the extent to which the critical control potential is exceeded. Another aspect of the arc-like characteristic is the so-called lock-in feature. A discharge device of the arc-like type when once rendered conductive continues to remain conductive regardless of the control electrode potential as long as the anode-cathode potential is sufficient to support the discharge.

As regards the foregoing comments, it is to be noted that they represent the general situation. Discharge devices which are responsive to variations in the control potential have been developed and where a system including such a discharge device involves the practice of our invention, we intend that it shall be regarded as lying within the scope thereof. It is to be noted, moreover, that while in Fig. 1 and in the other views our invention is illustrated as applied to

hot cathode discharge devices 19, 21 and 23, it may also be utilized with discharge devices in which cathodes of other types are utilized. For example, the hot cathode 33 may be replaced by a mercury pool or a deposit of lead or cadmium or any other metal which is either continuously maintained energized by a keep-alive electrode or is reenergized at suitable intervals by a make-alive electrode operating somewhat as a control electrode. The make-alive electrode may be external to the container of the discharge device or it may be internal and in contact with the pool or deposit as in the "Ignitron" tubes. The hot cathode 33 may also be replaced by a so-called cold cathode as in the Westinghouse cold cathode "Grid Glow" tube designated as KU-618 in the art. Apparatus incorporating discharge devices of the type just mentioned in lieu of the devices 19, 21 and 23 and involving the general features of our invention are within the scope thereof.

The control electrodes 35 of the discharge devices 19, 21 and 23 are connected through suitable resistors 37, 39 and 41 to a common point 43. The cathodes 33 of the discharge devices are also connected to a common point 45 which is the same electrically as the positive terminal of the load 17. Between the common control-electrode point 43 and the common cathode point 45 a composite control potential is impressed. One component of this potential is applied by a direct-current source such as a battery 47. The positive terminal of the source 47 is connected to the point 43 and its negative terminal is connected to the variable tap 49 of a potentiometer 51 connected across the load 17. The source 47 is of a magnitude that is large compared to the critical control potential of the discharge devices 19, 21 and 23 and the relationship in the magnitude of the quantities is such that the random variations in critical control potential which arise in a single discharge device 19, 21 or 23 or between the different discharge devices are substantially masked.

The other component of the control potential is provided between the movable tap 49 of the potentiometer 51 and the cathode common point 45. The latter potential is of such magnitude and polarity that the total potential exceeds the critical control potential periodically at intervals depending on the magnitude of the power which is to be supplied to the load 17.

The system operates to automatically maintain the potential supplied to the load 17 independent of variations in the potential of the source 47. The functioning of the apparatus is illustrated in Fig. 2. In curve A of this view, the potential difference between the cathode 33 of an energized discharge device and the neutral point 29 is plotted as a function of time. It will be noted that inasmuch as the potential drop through the discharge devices 19, 21 and 23, when they are energized, is comparatively small, this plot represents substantially the potentials supplied between the neutral point 29 and the terminals of the secondary windings 25, 27 and 28 of the transformer 18.

Potential is plotted vertically and time horizontally. The abscissa represents the potential of the neutral point 29. The heavy line portions 53 of the full line half waves 55 in curve A represent a normal condition of operation. The heavy line portions 59 of the broken line half waves 61 represent a hypothetical condition which exists when an increase occurs in the potential of the source 47 corresponding to the difference between

the heights of the broken line curves 55 and the full line loops 59.

When the apparatus is in operation, the discharge device 19, 21 or 23, corresponding to each phase, is conductive until the discharge device corresponding to the subsequent phase is energized. The loop portions 53 and 59 represent the conductive conditions of the successive discharge devices when the source potential corresponds respectively to loops 55 and 61. During a short transition period the discharge device (say 19) which is being extinguished and the discharge device (say 21) which is being energized are both conductive simultaneously. The transition interval is known as the commutation period and is represented in curve A by the two vertical lines 63 and 65 which are separated by a substantially horizontal line 67 between each pair of portions 53 of loops 55 and by corresponding lines 69, 71 and 73 for loops 61.

The successive discharge devices 19, 21 and 23 are, of course, not energized at random. Each discharge device is in its turn rendered conductive at the instance when the total control potential exceeds the critical control potential. It is from the timing of the occurrence of this event that an essential feature of our invention arises. It happens that for the potentials represented by the broken line loops 61, this instant occurs later than for the potentials represented by the full line loops 55 and the timing is such that the load potential remains constant. This aspect of our invention can be seen from the other curves shown in Fig. 2.

In curve B the potential between the cathodes 33 and the conductor 75 from the load 17 to the reactor 30 is plotted as a function of time. Again potential is plotted vertically and time horizontally. The abscissa now, however, corresponds to the potential of conductor 75. The full line loops 71 correspond to the full line loops 53 of curve A and the broken line loops 79 correspond to the broken line loops 61 of curve A. The potential variations are not as irregular as those represented in curve A by reason of the smoothing effect of the reactor 30, and the corresponding loops 71 and 79 are, therefore, not so jagged as the corresponding loop portions 53-63-67-65 and 59-69-73-71.

Since the cathodes 33 are connected to a common point 45, the waves 71 and 79 in curve B correspond to the potential difference between the point 45 and the conductor 75 and, therefore, between the lower terminal and the upper terminal of the potentiometer 51. The actual potential impressed between the control electrodes 35 and the cathodes 33 of the discharge devices 19, 21 and 23 includes a potential derived from potentiometer 51 and may be derived from curve B. It is illustrated in curve C. Here potential is again plotted vertically and time horizontally, but the abscissa corresponds to the potential of the cathodes 33. The horizontal line 81 above the abscissa corresponds to the potential supplied by the battery 47 in the control circuit. The full line loops 83 and the broken line loops 85 of medium weight at a considerable distance below the abscissa correspond to the potential difference between the movable tap 49 of the potentiometer 51 and the cathodes 33. The horizontal line 87 just below the abscissa corresponds to the critical control potential of the discharge devices. The heavy full line and broken line loops 89 and 91 correspond to the sum of the potential derived from the potentiometer 51 and the battery po-

tential. It will be noted that the latter loops intersect the critical control potential line 87 at nodal points 93 and 95, respectively, which correspond to the transition from one energized discharge device 19, 21 or 23 to the subsequent one.

The curves of Fig. 2 represent the natural operation of the apparatus. Consider the full line heavy loop 89 on the extreme left of curve C, assuming at the same time that the potential applied to the discharge devices 19, 21 and 23 corresponds to half wave 55. In correspondence with the left-hand loop 89, the control potential impressed on the discharge devices rises from a value substantially below the critical potential to the value of the critical potential represented by the second nodal point 93 from the left. During all this time one of the discharge devices (say 19) which corresponds to the first phase 25, has been energized and the current transmitted therethrough has swelled and decreased in accordance with loop portion 53. At the instant corresponding to the second nodal point from the left, the discharge device (say 21) corresponding to the second phase 27 is energized, since the anode-cathode potential applied to it is greater than the anode-cathode potential applied to the first phase. The corresponding control potential now becomes more negative, as illustrated, by the central heavy full line wave 89 as the current flow through the load increases, then it becomes more positive as the current decreases, until the instant corresponding to the third nodal point 93. Here the discharge device (say 23) corresponding to phase 28, is energized and the above procedure again repeated, producing the condition represented by the right-hand loop 89. The energization of device 23 is followed by the energization of device 19, and the above described steps are thus repeated until the current flow is for some reason interrupted or changed.

If a condition corresponding to the broken line loops 61 exists, the critical control potential line 87 will be cut at a later instant as is illustrated by the broken line loops 91 and the nodal points 95 and the ignition of the discharge devices will be correspondingly delayed. It is apparent that the load potential will now assume a value smaller than would be expected from the increase in source potential and in actual practice we have found that the load potential remains substantially constant.

While the fact that the load potential is constant in spite of variations in the source potential has been demonstrated by us conclusively by experiment, it may also be demonstrated mathematically.

Let

E =the potential of the battery 47,

V =the load potential,

e_g =the control potential,

α =a fraction represented by the setting of the potentiometer 51,

then at the nodal points:

$$e_g = E - \alpha V$$

$$V = \frac{E - e_g}{\alpha}$$

and since E is large enough to mask variations in e_g , V is constant.

As regards the relative magnitudes of the potentials utilized in the practice of our invention, we have found that the potential of the battery 47 should be of the order of 90 volts for discharge devices 19, 21 and 23 that have a critical potential

of the order of 12 volts. In one application of our invention we have utilized discharge devices of the type that have a critical control potential of plus 12 volts, and we have used a battery potential of 90 volts. It is to be noted that for a critical control potential of plus 12 volts, the critical control potential line 87 of curve C would be above rather than below the time axis.

Where the load current is to be maintained independent of variations in the load potential or is to vary in a predetermined manner with the load potential, the simple arrangement shown in Fig. 1 does not suffice and the arrangement shown in Fig. 3 should be utilized. In the modification shown in Fig. 3, the elements of Fig. 1 are incorporated and in addition a potential substantially proportional to the load current is superimposed on the battery potential and the potentiometer potential. The latter potential is derived from the source 11 through current transformers 91, 99 and 101 coupled to the conductors 103, 105, and 107, respectively, from the source to the primary 109 of the supply transformer 13. The transformers 91, 99 and 101 supply a variable resistor 111 through a plurality of rectifiers 113, 115 and 117. A variable capacitor 119 is connected between the movable tap 121 of the resistor 111 and one of its terminals. The capacitor 119 operates to smooth out the potential supplied by the transformers 91, 99 and 101 and may on occasions be omitted entirely.

The movable tap 121 of the resistor 111 and its left-hand terminal are connected in the control circuit of the discharge devices 19, 21 and 23 through a suitable reversing switch 123, so that the potential derived from the resistor may have either a positive or a negative polarity in the control circuit depending on the position of the switch. The potential impressed by reason of the current flow through the resistor 111 is to a fair approximation proportional to the load current, and thus operates to provide the necessary compensation for the variations in the current. For proper adjustment of the resistor 111 and the reversing switch 123, the load potential may be rendered substantially constant in spite of variations in the load current. This condition is designated in the art as flat compounding. Differential compounding or cumulative compounding may be attained by properly raising the magnitude of the potential supplied by the resistor 111 and closing the reversing switch 123 so that the potential supplied is of the proper polarity. Thus it is seen that any desired characteristic for the supply of power to the load 11 may be attained.

Using an arrangement such as is shown in Fig. 3, but with the movable tap 49 of the potentiometer 51 connected to the common cathode point 45, we have made measurements of the direct-current load potential as a function of the direct-current load current for various magnitudes of the resistor 111 through which the compounding potential is supplied. Certain of the results of these measurements are shown in Fig. 4, in which the direct-current load potential is plotted as a function of the direct-current load current. Potential is plotted vertically and current horizontally.

Three curves 125, 127 and 129 are reproduced, the curve 125 on the extreme left representing a large value of resistance, the center curve 127 a medium value of resistance, and the curve 129 on the extreme right a small value of the resistance. As can be seen from the plot, the system shown

Fig. 3 with the potentiometer potential zero as a rather interesting characteristic. Up to a certain potential of the order of 280 volts, the current is substantially constant as the potential is increased and the condition is represented by substantially vertical lines 131, 133 and 135. Above this potential the potential is substantially constant as the current decreases and the condition is represented by substantially horizontal lines 31, 139 and 141. The latter portion of the curves represents the condition which exists in the system when at a given current the load potential becomes so large that the source potential is insufficient to maintain the current. The lines 131, 33 and 135 represent the condition when for a given current the load potential is of such magnitude that the source potential is sufficient to maintain the current.

The property of the apparatus that is illustrated in Fig. 4 may with advantage be utilized in a system such as is shown in Fig. 5. In the modification shown in this view, the armature 143 of a direct-current motor 145 with independent excitation 147, is supplied from the output of a system such as is shown in Fig. 3. The armature of the motor is connected between the reactor 30 and the common junction point 45 of the cathodes 33. The exciting winding 149 of the motor is supplied independently from the main source through an auxiliary transformer 151 (or a source of any other type) and through an auxiliary discharge device 153. The latter may be a gaseous or a high vacuum tube having an anode 155, a hot cathode 157 and a control electrode 159 or any other discharge device of the various types mentioned hereinabove. The discharge device 153 is controlled through a photo-electric cell 161 connected between its control electrode 159 and its anode 155. By varying the radiation impinging on the photo-electric cell 161, the potential impressed between the anode 155 and the control electrode 159 is varied and thus the excitation of the motor, and, accordingly, its speed is controlled.

In lieu of the resistor 111 and the reversing switch 123 of the apparatus shown in Fig. 3, an auxiliary potentiometer 163 with a center tap 165 and a variable tap 167, which may be displaced on both sides of the center tap is utilized. By sliding the movable tap 167 from one side of the center tap 165 to the other, the polarity of the potential impressed from the current transformers may be varied. However, as a general rule, we prefer to operate with the potential supplied by the potentiometer 163 of the opposite polarity as the potential supplied by the battery 47.

It is seen that the energy consumed by the motor 145 may be controlled by shifting the movable tap of the potentiometer 163.

Depending upon the resistance of the auxiliary potentiometer 163 that is in the control circuit of the discharge devices 19, 21 and 23, the motor 145 has a characteristic corresponding to one or the other of the curves 125, 127 or 129, reproduced in Fig. 4. When power is first applied to the system, the motor begins to rotate and its speed gradually increases for an interval of time that may be designated as the starting period. During the starting period the system is operating along the lines 131, 133 or 135 and the motor draws constant current of a predetermined value, depending on the resistance in the control circuit, while the potential manifested at the terminals of the armature 143 (the peak electromotive

force) increases. The potential continues to increase with the current constant until the motor 145 attains its operating speed. At this point the system operates along the lines 137, 139 or 141, and the load potential becomes constant; that is to say, the back electromotive force of the motor and its speed become substantially constant.

Accordingly, an analysis of the curves 125, 127 and 129 as they apply to the system shown in Fig. 5 reveals that during the starting period the current drawn by the motor 145 is substantially constant, and, therefore, the torque is constant. During the operating period, the potential is substantially constant and although the current may vary, the speed remains substantially constant. In a system such as is shown in Fig. 5, starting equipment is eliminated and the torque may be high because normal direct-current motors such as 145 may be used at potentials for which they are best adapted. The speed may be controlled by controlling the field excitation and this object may be accomplished by utilizing an element of such small space and power requirements as a photo-electric cell 161.

In accordance with the foregoing principles, the maximum permissible transient load torque is equal to the starting torque. The latter may be set by the operator with the potentiometer 163 in the control circuit, and as is the usual case, may be of from 1 to 3 times the normal torque. The starting current may be reduced at any time below the maximum permissible value by inserting a resistor 169 in series with the potentiometer 163 as is illustrated in Fig. 6 for example. The resistor 169 in the modification shown in Fig. 6 may be connected in the circuit after the motor has started by a suitable two pole switch 171. The movable contactor 173 of the switch 171 is connected to the movable tap 167 of the auxiliary potentiometer 163, one pole 175 is connected to the control electrode common point 43 and the other pole 177 is connected to one terminal of the resistor 169, its other terminal being connected to the point 43.

In Fig. 7, the load current for a system, such as is shown in Fig. 3, is plotted as a function of the potential of the battery 47 for the condition in which the potential supplied by the main potentiometer 51 is zero. Current is plotted vertically and potential horizontally. The upper curve 179 represents the variation in direct-current as a function of the battery potential for a short circuit across the load terminals and the lower curve 181 represents the function for a finite load 17—specifically 58 ohms. The short circuit curve 179 is of particular interest. The current output varies continuously without any critical points from zero to a considerable value. This property of the apparatus which may be important in such applications as welding, for example, cannot be obtained with any other arrangement known to us than the one disclosed here. An ordinary phase shift controlled rectifier is critical to the phase adjustment when the load is a short circuit. In such a case, the output current of the rectifier is small for certain degrees phase angle and attains full value for a variation of 2 or 3 degrees in phase from this value.

It may be that other conditions of operation are desired than the ones discussed heretofore. For example, it may be desired that the load current should remain constant independent of variations in the source potential. Another characteristic which is sometimes desired in practice

is a load potential which is constant independent of variations in the load current. Both of these conditions may be attained by utilizing so-called potential compounding alone or in combination with current compounding.

An arrangement incorporating this feature is shown in Fig. 8. In addition to the potential derived from the current transformers 97, 99 and 101, the battery potential and the potentiometer potential, a potential is impressed in the control circuit of the discharge devices which is derived from an auxiliary potential transformer 183. The transformer 183 is of the ordinary delta-star type and supplies a second auxiliary potentiometer 185 through rectifiers 187, 189 and 191. The 15 potentiometer 185 is provided with a variable tap 193 which is connected to the common point 43 of the control electrodes 35, one of its terminal taps is connected to the neutral point 195 of the secondary 197 of the auxiliary transformer 183 and 20 the other to the poles 199 and 201 of the reversible switch 123 through which the potential derived from the current transformers 97, 99 and 101 is impressed in the control circuit. The potential derived from the potential transformer 183 is 25 thus superimposed on the other potentials in the control circuit. If, as is the case at times, it is desirable that only potential compounding be utilized, the resistor 111 supplied from the current transformers 97, 99 and 101 may be short 30 circuited by moving the movable tap to the upper terminal. However, in general, both current compounding and potential compounding is desirable, so that potential is supplied by both the current 35 transformers and the auxiliary potential transformer.

Our invention may also be applied to a system in which two sets 203 and 205 of three discharge devices 207, 209 and 211 and 213, 215 and 217, each are interposed between the load 17 and the 40 source. In such a case a transformer 218, with a double Y secondary 219 is utilized and the discharged devices 207, 209, 211, 213, 215 and 217 are connected to the windings 221, 223, 225, 227, 229 and 231 of the secondary. The potentials are supplied in the control circuits of the discharge devices in the same manner as in the single Y arrangement shown in the other views through potentiometer 51 with the variable tap 49 and the battery 47. The movable tap 49 of the potentiometer 51 is connected in series with the battery 47, the positive terminal of which is, in turn, connected through the reversing switch 123 to the current compounding resistor 111 and potential compounding potentiometer 185 to the control electrode common point 43. Between the neutral points 233 and 235 of the winding sets 237 and 239 of the secondary 219, a reactor 241 with an intermediate tap 243 is connected. The intermediate tap 243 is connected to the load 17.

Our invention has been disclosed herein as applied to various systems. A number of changes can be made in these systems without departing from the scope of our invention. It is to be noted, for example, that the combination of the variable current-compounding resistors 111 and the reversing switches 123 may be everywhere replaced by variable potentiometers 163, such as are utilized, for example, in the modifications shown in Figs 5 and 6.

In the modification shown in Fig. 9, a number of changes may be made and for that matter the changes may be added to the other modifications in cases where they are of advantage. One change which we regard as of some importance is 75

the insertion of an alternating current potential in the individual control conductors of the discharge devices 207, 209, 211, 213, 215 and 217. For this purpose a so-called grid transformer may be utilized. It may consist of a star-connected arrangement with 6 windings. Each of the windings may be connected in the conductor leading from a control electrode resistor 245, 247, 249, 251, 253 and 255, respectively, and the neutral point may be connected to the conductor 257 which in Fig. 9 is connected to the variable tap 193 of the potential compounding potentiometer 185. The remainder of the connections to the variable tap 49 of the main potentiometer 51 and thence to the load 17 may be the same as shown in Fig. 9.

Finally it is to be noted that while the discharge devices 19, 21, 23, 207, 209, 211, 213, 215 and 217 are shown as discrete elements, they may at times be replaced by discharge paths, all or some of which may be disposed in a common container and one or more electrodes 31, 33 or 35 of which may be common to all or some of the paths.

Although we have shown and described certain specific embodiments of our invention, we are fully aware that many modifications thereof are possible. Our invention, therefore, is not to be restricted except insofar as is necessitated by the prior art and by the spirit of the appended claims.

We claim as our invention:

1. Apparatus for supplying power from a source of electrical energy to a load comprising a discharge path having a plurality of principal electrodes and a control electrode and a gaseous medium interposed between said source and said load, said load being supplied through said discharge path, means for impressing a potential of one polarity between said control electrode and one of said principal electrodes, said potential being of a magnitude that is sufficiently large to mask random fluctuations in the critical potential of said discharge path and means for superimposing a potential, dependent on the magnitude of the output potential supplying said load and of opposite polarity to said first-named potential, on said first-named potential, said last-named potential being of such magnitude that the critical control potential of said discharge path is at times exceeded.

2. Apparatus for supplying power from a source of electrical energy to a load comprising a discharge path having a plurality of principal electrodes and a control electrode and a gaseous medium interposed between said source and said load, said load being supplied through said discharge path, means for impressing a potential between said control electrode and one of said principal electrodes of a polarity such as to tend to energize said discharge path, said potential being of a magnitude that is sufficiently large to mask random fluctuations in the critical control potential of said discharge path and means for superimposing a potential, dependent on the magnitude of the output potential supplying said load and of opposite polarity to said first-named potential, on said first-named potential, said last-named potential being of such magnitude that the critical control potential of said discharge path is at times exceeded.

3. Apparatus for supplying power from a source of electrical energy to a load comprising a discharge path having a plurality of principal electrodes and a control electrode and a gaseous medium interposed between said source and said load, said load being supplied through said dis-

charge path, means for impressing a potential of one polarity between said control electrode and one of said principal electrodes, said potential being of a magnitude that is so large as to mask random fluctuations in the critical control potential of said discharge path, means for superimposing a potential, dependent on the magnitude of the output potential supplying said load and of opposite polarity to said first-named potential, on said first-named potential, said last-named potential being of such magnitude that the critical control potential of said discharge path is at times exceeded and means for superimposing on said first-named and second-named potentials a potential dependent on the current flow from said source.

4. Apparatus for supplying power from a source of electrical energy to a load comprising a discharge path having a plurality of principal electrodes and a control electrode and a gaseous medium interposed between said source and said load, said load being supplied through said discharge path, means for impressing a potential of one polarity between said control electrode and one of said principal electrodes, said potential being of a magnitude that is so large as to mask random fluctuations in the critical potential of said discharge path, means for superimposing a potential, dependent on the magnitude of the output potential supplying said load and of opposite polarity to said first-named potential, on said first-named potential, said last-named potential being of such magnitude that the critical control potential of said discharge path is at times exceeded and means for superimposing on said first-named and second-named potentials a potential dependent on the potential of said source when power is being supplied to said load.

5. Apparatus for supplying power from a source of electrical energy to a load comprising a discharge path having a plurality of principal electrodes and a control electrode and a gaseous medium interposed between said source and said load, said load being supplied through said discharge path, means for impressing a potential of one polarity between said control electrode and one of said principal electrodes, said potential being of a magnitude that is so large as to mask random fluctuations in the critical control potential of said discharge path, means for superimposing a potential, dependent on the magnitude of the output potential supplying said load and of opposite polarity to said first-named potential, on said first-named potential, said last-named potential being of such magnitude that the critical control potential of said discharge path is at times exceeded, means for superimposing on said first-named and second-named potentials a potential dependent on the current flow from said source, and means for superimposing on all said potentials a potential dependent on the potential of said source when power is being supplied to said load.

6. Apparatus for supplying power from a source of electrical energy to a load of the type that requires a predetermined compounding comprising a discharge path having a plurality of principal electrodes and a control electrode and a gaseous medium interposed between said source and said load, said load being supplied through said discharge path, means for impressing a potential of one polarity between said control electrode and one of said principal electrodes, said potential being of a magnitude that is sufficiently large to mask random fluctuations in the critical con-

trol potential of said discharge path, means for superimposing a potential, dependent on the magnitude of the output potential of said load and of opposite polarity to said first-named potential, on said first-named potential, said last-named potential being of such magnitude that the critical control potential of said discharge path is at times exceeded, means for superimposing on said first-named and second-named potentials a potential dependent on the current flow from said source, and means for adjusting the last said potential to select a particular compounding for said load.

7. Apparatus for supplying power from a periodic current source of electrical energy to a load comprising a discharge path having a plurality of principal electrodes and a control electrode and a gaseous medium interposed between said source and said load, said load being supplied through said discharge path, means for impressing a potential of one polarity between said control electrode and one of said principal electrodes, said potential being of a magnitude that is so large as to mask random fluctuations in the critical control potential of said discharge path and means for superimposing a potential, dependent on the magnitude of the output potential supplying said load and of opposite polarity to said first-named potential, on said first-named potential, said last-named potential being of such magnitude that the critical control potential of said discharge path is periodically exceeded.

8. Apparatus for supplying power from a periodic current source of electrical energy to a load comprising a discharge path having a plurality of principal electrodes and a control electrode and a gaseous medium interposed between said source and said load, said load being supplied through said discharge path, means for impressing a potential of one polarity and of substantially constant magnitude between said control electrode and one of said principal electrodes, said potential being of a magnitude that is so large as to mask random fluctuations in the critical control potential of said discharge path and means for superimposing a potential, dependent on the magnitude of the output potential supplying said load and of opposite polarity to said first-named potential, on said first-named potential, said last-named potential being of such magnitude that the critical control potential of said discharge path is periodically exceeded.

9. Apparatus for supplying power from an alternating current source of electrical energy to a load comprising a discharge path having a plurality of principal electrodes and a control electrode and a gaseous medium interposed between said source and said load, said load being supplied through said discharge path, means for impressing a potential of one polarity between said control electrode and one of said principal electrodes, said potential being of a magnitude that is so large as to mask random fluctuations in the critical control potential of said discharge path and means for superimposing a potential, dependent on the magnitude of the output potential supplying said load and of opposite polarity to said first-named potential, on said first-named potential, said last-named potential being of such magnitude that the critical control potential of said discharge path is periodically exceeded.

10. Apparatus for supplying power from a polyphase source of electrical energy to a load comprising a discharge path having in effect a

plurality of principal electrodes and a control electrode and a gaseous medium interposed between each phase of said source and said load, said load being supplied through said discharge path, means for impressing a potential of one polarity between the control electrodes and one of the principal electrodes of all of said discharge paths, said potential being of a magnitude that is so large as to mask random fluctuations in the critical control potential of said discharge paths and means for superimposing a potential, dependent on the magnitude of the output potential supplying said load and of opposite polarity to said first-named potential, on said first-named potential, said last-named potential being of such magnitude that the critical control potential of said discharge paths is periodically exceeded by the total potential.

11. Apparatus for supplying power from a polyphase source of electrical energy to a direct-current load comprising a discharge path having in effect an anode, a cathode and a control electrode and a gaseous medium interposed between each phase of said source and said load, said load being supplied through said discharge paths, means for impressing a potential of positive polarity between the control electrodes and the cathodes of all said discharge paths, said potential being of a magnitude that is large compared to the critical control potential of said discharge paths and means for superimposing on said positive polarity potential a potential of negative polarity, that varies in dependence upon the variation of the output potential supplying said load, and that has a magnitude such that the control potential of said discharge paths is periodically exceeded by the total potential.

12. Apparatus according to claim 11 characterized by the fact that the positive polarity potential is of such magnitude that it masks the variations of the critical control potential arising in any one discharge path or between the discharge paths.

13. Apparatus for supplying power from a polyphase source of electrical energy to a direct-current load comprising a discharge path having in effect an anode, a cathode and a control electrode and a gaseous medium interposed between each phase of said source and said load, said load being supplied through said discharge paths, means for impressing a potential of positive polarity between the control electrodes and the cathodes of all said discharge paths, said potential being of a magnitude that is so large as to mask random fluctuations in the critical control potential of said discharge paths, means for superimposing on said positive polarity potential a potential of negative polarity, that varies in dependence upon the variation of the output potential supplying said load, and that has a magnitude such that the critical control potential of said discharge paths is periodically exceeded by the total potential and means for superimposing on said potentials of positive and negative polarity a potential dependent upon the magnitude of the load current to compensate for load current variations.

14. Apparatus for supplying power from a polyphase source of electrical energy to a direct-current load of the type that requires a predetermined compounding comprising a discharge path having in effect an anode, a cathode and a control electrode and a gaseous medium interposed between each phase of said source and said load, said load being supplied through said dis-

charge paths, means for impressing a potential of positive polarity between the control electrodes and the cathodes of all said discharge paths, said potential being of a magnitude that is sufficiently large to mask random fluctuations in the critical control potential of said discharge paths, means for superimposing on said positive polarity potential a potential of negative polarity, that varies in dependence upon the variation of the output potential supplying said load, and that has a magnitude such that the control potential of said discharge paths is periodically exceeded by the total potential and means for superimposing on said potentials of positive and negative polarity a potential dependent upon the magnitude of the load current to adjust the compounding.

15. Apparatus for supplying power from a polyphase source of electrical energy to a direct-current load comprising a discharge path having in effect an anode, a cathode and a control electrode and a gaseous medium interposed between each phase of said source and said load, said load being supplied through said discharge paths, means for impressing a potential of positive polarity between the control electrodes and the cathodes of all said discharge paths, said potential being of a magnitude that is so large as to mask random fluctuations in the critical control potential of said discharge paths, means for superimposing on said positive polarity potential a potential of negative polarity, that varies in proportion with the output potential supplying said load, and that has a magnitude such that the critical control potential of said discharge paths is periodically exceeded by the total potential and means for superimposing on said potentials of positive and negative polarity a potential proportional to the magnitude of the load current to compensate for load current variations.

16. Apparatus for supplying power from a source of electrical energy to an electro-dynamic machine having an armature and independent excitation means comprising an electric discharge path having a control electrode and a plurality of principal electrodes and a gaseous medium, interposed between said armature and said source, said armature being supplied through said discharge path, means for impressing a potential of magnitude sufficiently large to mask random fluctuations in the critical control potential of said discharge path between said control electrode and one of said principal electrodes and means for superimposing on said first-named potential a potential dependent on the magnitude of the current flow through said armature.

17. Apparatus for supplying power from a source of electrical energy to an electro-dynamic machine having an armature and independent excitation means, comprising an electric discharge path, having a control electrode and a plurality of principal electrodes and a gaseous medium, interposed between said armature and said source, said armature being supplied through said discharge path, means for impressing a potential of magnitude sufficiently large to mask random fluctuations in the critical control potential of said discharge path between said control electrode and one of said principal electrodes and means for superimposing on said first-named potential a potential proportional to the magnitude of the current flow through said armature up to armature potentials of magnitudes for which the potential of the source is sufficient.

18. Apparatus for supplying power from an alternating current source of electrical energy to an electro-dynamic machine having an armature and independent excitation means, comprising an electric discharge path, having a control electrode, an anode and a cathode and a gaseous medium, interposed between said armature and said source, said armature being supplied through said discharge path, means for impressing a potential of magnitude sufficiently large to mask random fluctuations in the critical control potential of said discharge path and of positive polarity between said control electrode and said cathode and means for superimposing on said first-named potential a potential of negative polarity dependent on the magnitude of the current flow through said armature.

19. Apparatus for supplying power from a polyphase source of electrical energy to an electro-dynamic machine having an armature and independent excitation means, comprising in effect an electric discharge path, having a control electrode, an anode and a cathode and a gaseous medium, interposed between said armature and each phase of said source, said armature being supplied through said discharge path, means for impressing a potential of magnitude so large as to mask the variations arising in the critical control potential of each said discharge path and between the critical control potentials of all said discharge paths and of positive polarity between the control electrode and the cathode of all said discharge paths and means for superimposing on said first-named potential a potential proportional to the magnitude of the current flow through said armature up to armature potentials of magnitudes for which the potential of said source is sufficient.

20. Apparatus according to claim 19 characterized by photo-sensitive means for controlling the excitation of the machine.

21. Apparatus for varying the supply of power from a source of alternating current to a load of the type that has the properties of a short circuit comprising an electric discharge path having a control electrode and a plurality of principal electrodes and a gaseous medium interposed between said source and said load through which current flows to said load, means for impressing a potential, proportional to the current flow from said source when said load is being supplied, between said control electrode and a principal electrode of said path and means for impressing a potential independent of the said current flow but variable in magnitude in accordance with the load current desired between the said control electrode and the last said principal electrode.

22. Apparatus for varying the supply of power from a source of alternating current to a load of the type that has the properties of a short circuit comprising an electric discharge path having a control electrode and a plurality of principal electrodes and a gaseous medium interposed between said source and said load through which current flows to said load, means for impressing a potential, proportional to the current flow from said source when said load is being supplied, between said control electrode and a principal electrode of said path and means for impressing a direct current potential independent of the said current flow but variable in magnitude in accordance with the load current desired between the said control electrode and the last said principal electrode.

23. Apparatus for varying the supply of power from a source of alternating current to a load of the type that has the properties of a short circuit comprising an electric discharge path having a control electrode and a plurality of principal electrodes and a gaseous medium interposed between said source and said load through which current flows to said load, means for impressing a direct current potential, proportional to the current flow from said source when said load is being supplied, between said control electrode and a principal electrode of said path and means for impressing a direct-current potential independent of the said current flow but variable in magnitude in accordance with the load current desired between the said control electrode and the last said principal electrode.

24. Apparatus for varying the supply of power from a source of alternating current to a load of the type that has the properties of a short circuit comprising an electric discharge path having a control electrode, an anode and a cathode and a gaseous medium interposed between said source and said load through which current flows to said load, means for impressing a direct current potential, proportional to the current flow from said source when said load is being supplied, between said control electrode and said cathode of said path and means for impressing a direct-current potential independent of the said current flow but variable in magnitude in accordance with the load current desired between the said control electrode and said cathode.

25. Apparatus for varying the supply of power from a source of alternating current to a load of the type that has the properties of a short circuit comprising an electric discharge path having a control electrode, an anode and a cathode and a gaseous medium interposed between said source and said load through which current flows to said load, means for impressing a direct current potential proportional to the current flow from said source, when said load is being supplied between said control electrode and said cathode of said path and means for impressing a direct-current potential independent of the said current flow but variable in magnitude in accordance with the load current desired between the said control electrode and said cathode, said variable potential being opposite in polarity to said proportional potential.

26. Apparatus for varying the supply of power from a source of alternating current to a load of the type that has the properties of a short circuit comprising an electric discharge path having a control electrode, an anode and a cathode and a gaseous medium interposed between said source and said load through which current flows to said load, means for impressing a direct current potential proportional to the current flow from said source, when said load is being supplied, between said control electrode and said cathode of said path and means for impressing a direct current potential independent of the said current flow but variable in magnitude in accordance with the load current desired between the said control electrode and said cathode, said variable potential being positive in polarity and said proportional potential being negative in polarity.
